UNITED STATES PATENT OFFICE.

JAMES SNEEDEN, OF WICHITA, KANSAS, ASSIGNOR OF ONE-THIRD TO ALBERT RALPH MURRAY, OF WICHITA, KANSAS.

HYDROCARBON-BURNING FURNACE.

1,063,077.

specification of Letters Patent.

Patented May 27, 1912.

Application filed April 2, 1912. Serial No. 688,108.

To all whom it may concern:

Be it known that I, JAMES SNEEDEN, a citizen of the United States, residing at Wichita, in the county of Sedgwick and State of Kansas, have invented certain new and useful Improvements in Hydrocarbon-Burning Furnaces, of which the following is a specification.

My invention relates to certain improvements in the construction and operation of fuel oil or hydro-carbon burners as applied to furnaces or steam boilers and heaters of every description.

Generally stated, it consists of an air compressor or blower suitably operated in conjunction with an oil pump to supply the requisite amount of air and oil for combustion, and the essential features of my invention are more fully shown in the accompanying drawings, where—

Figure 1 is an elevation of one embodiment of my device, representing an ordinary hot water heating plant; Fig. 2 a vertical section of Fig. 1; Fig. 3 is an elevation in smaller scale of the motor, air compressor and pump; and Fig. 4 is a detail view in larger scale of the regulating valve.

A is the motor and B the air compressor; C is the oil pump arranged to operate in unison and D the air pipe leading to the tank H.

E are the pipes for heating the air in its passage to the burners P.

F is the oil pipe and coils for heating the oil in its passage from the pump to the burners or burner. The coils F² are shown in Fig. 2 at the top of an ordinary hot water heating plant but may be located anywhere convenient but far enough away to heat but not burn the oil in its passage through the coils *en route* to the burners. It will be seen that the air pipe E² is placed in the side of the furnace or firebox, so that the air in its passage through it, is heated to such a degree that, when the air and oil unite at the burner, they readily ignite, that being the ideal condition essential to perfect combustion.

G (see Figs. 1, 2 and 4) is the regulating valve for controlling the amount of the mixture requisite to different degrees of heat. The valves M and O on the connections E¹ and F¹, between the valve G and the pipes E and F respectively serve as a cutoff and when proper amount of air and oil has been

turned on, it may be varied up or down by the regulating valve G to suit. The air is pumped into a pressure tank H and its pressure is controlled by the regulator or pop N on the tank H. This at all times secures a uniform pressure for the air, and owing to the objection, on part of insurance companies to all forms of gravity feeds for the oil, I, in practice, place the oil tank or reservoir underground and preferably lift the oil and force it through the coils F at such a pressure as will insure its reaching the burners unimpaired by the heat in the coils. By means of an overflow pipe F², the surplus oil is returned to the reservoir, it being my object to avoid any accumulation of oil near the furnace which might prove a menace or fruitful source of fire. There is likewise an air return pipe E². The air compressor pump is run by a belt B¹ from the motor A and the oil pump C is in turn operated by a belt C¹ from the compressor shaft, so that in case the motor should fail, the air and oil pressure would fall and the fire go out. It will be noted that air and oil, though heated in separate coils, do not unite until they reach the burners or nozzles, where they are ignited within the furnace proper, and I so proportion my air and oil pipes, that it will only be necessary to use the valves M and O, and that by merely opening them full, the requisite amount of air and oil is at all times assured independent of any form of regulating valve or mixer.

I claim:

1. In a hydrocarbon burning furnace, having a combustion chamber, in combination a source of compressed air supply, a source of liquid fuel supply, a burner in said chamber, and individual conduits to said burner from said sources of air and fuel supply; said compressed air conduit comprising a coiled pipe in the path of the flame within the combustion chamber; said liquid fuel conduit comprising a coiled pipe in the combustion chamber and removed from the flame, whereby the fuel is heated to a desired temperature.

2. In a hydrocarbon burning furnace, having a combustion chamber, in combination a source of compressed air supply, a source of liquid fuel supply, a burner in said chamber, and individual conduits to said burner from said sources of air and fuel supply; said compressed air conduit com-

prising a coiled pipe in the path of the flame within the combustion chamber; said liquid fuel conduit comprising a coiled pipe in the combustion chamber and removed from the flame, whereby the fuel is heated to a desired temperature; an inlet valve on said burner controlling the admission of both air and fuel to said burner, and individual valves in said conduits, whereby the relative

quantity of air and fuel will be adjusted in 10 the combustion mixture admitted to the burner through said inlet valve.

The foregoing specification signed at Wichita Kans. this 13th day of March, 1912.

JAMES SNEDDEN.

In presence of—

ALBERT RALPH MURRAY,
ISAAC HAYS SALISBURY.
